US00D964334S

(12) **United States Design Patent** (10) **Patent No.:** **US D964,334 S**
(45) **Date of Patent:** **** Sep. 20, 2022**

(54) **WIRELESS CONNECTIVITY DEVICE**

(71) Applicant: **Amazon Technologies, Inc.**, Seattle, WA (US)

(72) Inventors: **Fred Bould**, Menlo Park, CA (US); **Jeremy Paul Wolf**, San Francisco, CA (US); **Jamie Starr Perin**, San Francisco, CA (US); **Robert Nicholas Dean**, San Francisco, CA (US)

(73) Assignee: **Amazon Technologies, Inc.**, Amazon, WA (US)

(**) Term: **15 Years**

(21) Appl. No.: **29/804,827**

(22) Filed: **Aug. 23, 2021**

Related U.S. Application Data

(62) Division of application No. 29/714,464, filed on Nov. 22, 2019, now Pat. No. Des. 931,842.

(51) **LOC (13) Cl.** **14-03**

(52) **U.S. Cl.**

USPC **D14/242**

(57) **CLAIM**

The ornamental design for a wireless connectivity device, as shown and described.

DESCRIPTION

FIG. 1 is a top, front, right-side perspective view of a wireless connectivity device;

FIG. 2 is a top, back, right-side perspective view thereof;

FIG. 3 is a bottom, front, left-side perspective view thereof;

FIG. 4 is a front view thereof;

FIG. 5 is a back view thereof;

FIG. 6 is a left-side view thereof;

FIG. 7 is a right-side view thereof;

FIG. 8 is a top view thereof; and,

FIG. 9 is a bottom view thereof.

The dashed broken lines depict portions of the wireless connectivity device that form no part of the claimed design.

1 Claim, 9 Drawing Sheets
